UNITED STATES PATENT OFFICE.

HAROLD E. SLADE, OF NEWARK, NEW JERSEY, ASSIGNOR TO BEAVER MACHINE & TOOL CO., INC., OF NEWARK, NEW JERSEY.

OUTLET RECEPTACLE.

Application filed February 16, 1924. Serial No. 693,195.

This invention has for its object to provide an improved form of convenience outlet receptacle that is economical to manufacture and at the same time of very substantial construction.

The improvement has to do with the contact members and a novel method of fastening the supporting strap to the body member.

10 As now made the supporting strap is generally fastened to the body member of the receptacle either by eyelets moulded into the composition and acting as rivets or by the use of screws.

15 In my improved receptacle I do not employ either of these methods but have devised a supporting strap in which tongues or clamping members are formed integrally, thus saving the cost of screws, eyelets, etc.

20 The following is a clear description and specification covering the invention and is to be considered in conjunction with the accompanying drawing in which:

Figure 1 is a plan view of the receptacle 25 assembled.

Figure 2 is a section taken on lines 1-1 Figure 1.

Figure 3 is a perspective view of one end of the supporting strap.

30 Figure 4 is a perspective taken along line 2-2 of Figure 2 and shows the method of assembling the contact members.

Figure 5 is a perspective of the contact member.

35 Figure 6 is a development of contact member Figure 5.

Figure 7 is a plan view showing another method of assembling the strap to the body member.

40 Figure 8 is a partial section along line 3-3 of Figure 7.

Figure 9 is an end elevation of the receptacle body member.

Figure 10 is a perspective of the end of the 45 receptacle body member.

Figure 11 is a perspective view of one end of the modified form of strap.

Referring to Figures 1 and 2; 1 is a base member made from any suitable insulating material such as porcelain, asbestos compounds etc., in which apertures 2-2 are provided to accommodate the parallel type of attachment plug cap prongs and angularly disposed to these apertures and connecting therewith are apertures 3-3, for the

accommodation of tandem type attachment plug prongs.

As the use and functions of an attachment plug cap are familiar to those versed in the art the caps and their associated prongs are 60 omitted from the drawings.

Extending from the lower side of the base member and connecting with the apertures 2-2 and 3-3, are recesses 4-4 in which the contact members, Fig. 5 and indicated 65 as 5-5 in Fig. 2, are housed.

The recesses 4-4 are so proportioned relatively to the contacts 5-5 that the latter have a floating action. This floating action eliminates strains between the contacts and 70 the prongs of the attachment plug cap if there is any tendency for them to be misaligned.

Associated with the contacts 5-5 is an insulating strip 6 which separates them electrically from the strap or supporting member 7. This supporting member is provided with means in the form of slots 8-8 for attaching the receptacles to the outlet box (not shown) and with threaded holes 9-9 for attaching the face plate (not shown) to the receptacle.

As shown in Figure 3, the strap or supporting member 7 is made from a single piece of metal formed so as to have a base element 10, perpendicular element 11 and projecting fastening lug 12. Cut from the base element 10 are resilient tongues 13-13. The perpendicular element 11 is slotted as indicated at 14-14 forming the clamping 80 lugs 15-15.

In assembling the receptacle the contacts 5-5 are placed in the recesses 4-4; the insulator 6 is placed over the contacts and the supporting strap 7 is placed over the insulator. The parts are then placed in a suitable device or fixture and pressure is brought to bear against the face of the body member 1 as indicated by arrows P-P, the clamping lugs 15-15 are then pressed inwardly as 95 indicated by arrows P¹-P¹ over the inclined surfaces 16-16 at the bottom of recesses 17-17. Any irregularities in thickness of the base 1 which would cause looseness in the strap is compensated for by the 100 resilient tongues 13-13.

An improved form of contact is shown in Figures 5 and 6 in which 18 is a base member, 19 is a binding post member provided with ears or projections 20-20 for 110

preventing the connecting wire from squeezing out from under the binding screw 21. From the base 18 is a contact member 22 flared as at 23, for engaging one side of a parallel blade of an attachment plug cap. At the end of and angularly disposed to the contact member 22 is an arm 24, flared as at 25, for engaging one side of a tandem blade of an attachment plug cap. From the base 10 member 18, and parallel with arm 24, is raised a second contact member 26, flared as at 27, for engaging the other side of the tandem blade of an attachment plug cap. At the end of and angularly disposed to 15 the contact member 26, is a second arm 28, flared as at 29, and parallel to contact member 22, for engaging the other side of the parallel blade of an attachment plug cap.

Thus a pair of these contacts are used in 20 a base in which either the tandem or parallel types of attachment plug caps may be inserted.

In the modified form of supporting strap as shown by Figs. 7-8-11 a slightly different method of assembling the strap to the receptacle base is used.

The strap member 7^a is substantially the same as that shown heretofore and designated as 7.

30 The difference in construction is that the slots 14-14 in members 11-11 Figure 3 are omitted and in their stead is cut and turned inward from members 11^a-11^a lugs or ledges 30-30 Figures 7-8-11.

35 The base member 1^a, Figures 7-8-9-10; is provided with recesses 31-31 at the extreme end portions 32-32. Leading up to the recesses 31-31 from both sides of the end portions 32-32 are inclines 33-33-40 33-33.

In the placing of the strap in its final position, the insulating strip 6^a is placed upon the resilient tongues 13^a-13^a-13^a-13^a cut from the base member 10^a of the strap, the base member 1^a is inserted edgewise between 45 the insulating strip 6 and the ledges 30-30 so that the ledges 30-30 rest upon the inclines 33-33.

By putting pressure on the edge of the base member 1^a the inclines 33-33 act as a 50 wedge whereby the resilient tongues 13^a-13^a are forced downward, allowing the entire strap member to move at right angles to the major axis of body until such time as the ledges 30-30 snap into the recesses 31-31 55 of the body member 1 and thereby become locked.

Having described my invention what I claim is:-

A contact member for an outlet receptacle comprising a base member, a binding screw member formed at right angles to said base member, a contact member formed at right angles to said base member, a second contact member formed at right angles to 65 said base member and at an obtuse angle to the first contact member; said first contact member being provided with a projecting member formed so as to be parallel to and coact with said second contact member; said second contact member being provided with a projecting member formed so as to be parallel to and coact with said first contact member; said coaction to produce a positive gripping action on both sides of an attachment plug cap blade when inserted between said contact members.

Signed by me this 14th day of February, 1924, at Newark, N. J.

HAROLD E. SLADE.
